UNITED STATES PATENT OFFICE.

HARMON P. ELLIOTT, OF CAMBRIDGE, MASSACHUSETTS.

STENCIL-PRINTING MACHINE.

Application filed February 14, 1924. Serial No. 692,840.

This invention relates to stencil printing machines and is a continuation in part of my co-pending application Serial No. 688,298, filed January 24, 1924.

5 Stencils are or may be maintained in alphabetical or equivalent order in trays and are placed in such order in the stencil printing machine and are run through the machine for the printing of addresses and the like and the used stencils are again placed in the same order in trays. It is very often desirable to select only certain stencils of the entire group for printing but is not practicable to locate and extract the desired 10 stencils from the trays.

An object of this invention is the provision of a stencil printing machine, and particularly a hand-operated machine, having means by which the entire group of stencils 20 may be run through the machine in the order in which they have been initially arranged, and means permitting the operator to select, during the run-off, only such stencils as are desired and print from such selected 25 stencils and to pass other stencils through the machine without printing therefrom.

In carrying out this invention, the stencils may be provided with indicating means as, for instance, one or more punch marks 30 to indicate the particular class or classes in which the stencil may be listed; and the punch marks may be located in a specific manner in or on the stencil. Indicating means, preferably adjustable, may be provided and so arranged that as the stencils are passing intermittently through the machine, the register of the indicating means with the punch mark of a stencil indicates 35 that the registering stencil is to be used for printing; and the machine is so operated as to print from the stencil. If, however, the indicating means and the punch mark of a stencil are not in register the machine may be operated to pass that stencil through the 40 machine without printing therefrom.

A further object of the invention is to improve the construction and operation of stencil printing machines.

Fig. 1 is a side elevation of a stencil printing machine constructed in accordance 50 with the invention.

Fig. 2 is an end elevation of the machine of Fig. 1, partly in section.

Fig. 3 is a partial sectional view taken along lines 3—3 of Fig. 1. 55

Fig. 4 is a partial vertical section of the machine taken along line 4—4 of Fig. 2.

Fig. 5 is a partial plan view of the stencil track and stencil holder and illustrating more particularly the arrangement of the 60 stencils therein and their relation with the stencil selecting means.

Fig. 6 is a detail illustrating more particularly the conjoint printing operation of the printing sectors and the dating attachment. 65

As here shown, the stencil printing machine embodying the invention is hand-operated and includes a base 10 which is adapted to rest upon a table or other suitable support. Said base 10 is formed with a flat top 11 which forms a table or bed adapted to support the work A, as envelopes, sheets, bills, and the like to be printed. 70

The type of stencil more particularly 75 adapted for use in this machine is shown most clearly in Fig. 5 and comprises a relatively stiff frame 12 having a window therein occupied by a stencil sheet 13, which sheet is adapted to bear the characters, as an address, to be imprinted. Said stencil sheet 13 is disposed to lie entirely within the opposite faces of the frame 12 as is indicated more clearly in Fig. 6, although the particular form of stencil is not of especial importance 80 so far as this invention is concerned. 85

The stencils are adapted to be moved above the bed 11 in parallel and spaced tracks 14 and 15 which tracks are formed or provided with grooves 16 in their opposed parallel faces, in which grooves the stencils are adapted to slide freely. A superimposed pile of stencils are adapted to be supported in position to be introduced one at a time into one end of the stencil track 95 whereby to be moved along said track for the printing of the impressions carried by them. The stencils are contained in a stencil holder carried by and disposed at one end of the stencil track. The stencil holder 100 may comprise the channelled end-plates 18 and 19, which plates may be secured to the

stencil tracks 14 and 15 by suitable means as screws 20, and said stencil holder thereby serves to provide a rigid support for the tracks.

5 A supporting bracket 21 may be secured to the base 10 of the machine at one side thereof, and extend upwardly, and over the bed 11 of said base and be secured to one of said tracks as the track 15 whereby to 10 support the track and the stencil holder in elevated position above and spaced from said bed 11. A superimposed pile of stencils is adapted to be supported freely within said stencil holder and in such position that the 15 lowermost stencil of the pile may be transferred from the pile into and moved along the track into a printing position.

The printing stencils are adapted to be discharged from the track into a stencil 20 receiver 23, which receiver is pivotally connected dependently with the ends of said tracks 14 and 15 as by means of a bracket 24.

The printing mechanism includes two 25 superimposed stencil driving and printing sectors 25 and 26, which sectors are approximately semicircular in shape and the faces thereof are covered with a relatively yielding material as rubber, for instance. The lower sector is fixed to an operating shaft 30 27 and said sector may extend through an aperture 28 in the bed 11 of the base 10. Said operating shaft 27 is journaled in a lever support 29, which support is pivoted at 30 to the base 10. The other end of said 35 lever support is engaged by a compression spring 31 whereby yieldingly to maintain the printing sector 26 in printing relation with the stencils in the stencil tracks and also with the work to be printed upon and 40 permit said sector to yield downwardly whereby to compensate for various thicknesses of the work. Said operating shaft 27 is extended freely through a vertically elongated aperture 33 in the base 10 and a gear 45 34 is fixed to the outer end thereof. The upper sector 25 is fixed to an operating shaft 35 and said shaft is supported in the spaced arms 36 and 37 of a bracket 38, which bracket is secured to the base 10. A gear 50 39 is fixed to the end of said shaft and meshes with the gear 34 and is of equal pitch diameter therewith whereby both sectors may be rotated at the same peripheral speed.

55 In accordance with this invention, means are provided whereby the stencil feeding mechanism may be operated without rotating the sectors. Said means includes an 60 upper sector. An operating handle 41 is carried loosely on said upper operating-shaft 35 and is secured thereon against unintentional detachment by suitable means as a washer 41^a and the screw 41^b, which screw is extended loosely through the washer and

is screw-threaded into the end of said shaft 35. Said handle is provided with an intermediate cylindrical portion 43, which portion may form a crank arm, and a spring-pressed pin 44 is slidably received within 70 said cylindrical portion 43. Said pin 44 is adapted to enter a recess in the end of said arm 40 whereby to lock said handle and arm releasably for conjoint rotation. Said arm may be released from said handle by 75 moving the pin toward the right, Fig. 2, whereby to remove the end of said pin from its normal position within the recess in said arm 40 and the handle may then be rotated independently of the sectors whereby independently to actuate the feeding mechanism.

Said arm 40 is provided with a laterally curved extension 40^a, which extension is adapted to form a cam face and guide said spring-pressed pin 44 to enter the recess in 80 said arm 40 upon a suitable movement of the operating handle 41. A latch 46 is secured pivotally to the bracket 38 and is adapted to engage, and support said arm 40 against movement in one direction, as against counterclockwise rotation, yet the latch is adapted to be moved about its pivot by said arm 40 whereby to permit said arm to rotate in a clockwise direction. Said latch is adapted to hold said arm stationary 85 when said operating handle 41 is rotated in a counterclockwise direction whereby to permit said pin 44 to be depressed for entering the locking aperture in said arm 40. Said latch is also arranged to hold said sectors in a stencil-disengaging position.

90 Stencils are fed successively from the pile of stencils in the stencil receiver and delivered into the stencil tracks in a position to be engaged by the printing sectors by 105 suitable means including the pusher 50. Said pusher is arranged to be reciprocated within the slots in the tracks 14 and 15 to engage the lowermost stencil of the pile and move it from its position under the pile 110 of stencils and into such position in the track that it may be engaged by the sectors 25 and 26, as said sectors are rotated, which sectors are arranged to move the stencils further along the track while simultaneously 115 recording the impressions borne by the stencils and moving the work. Said pusher is reciprocated by suitable means including a connecting rod 52, which connecting rod is arranged for detachable operative connection with the operating handle 41, for a purpose with which this invention is not concerned.

120 As thus arranged, with the connecting rod in operative connection with the operating handle, the pusher 50 is given one complete reciprocation at each complete revolution of the handle, whereby to move the lowermost stencil from the pile of stencils into the stencil track and in a position to be engaged 125 130

and moved further along the track by the sectors 25 and 26. Said sectors are so arranged and timed with relation to the movements of the pusher as to engage a stencil 5 moved into the track from the stencil receiver and move it along the track while the pusher is on its outward stroke.

The operation of the machine so far described is substantially as follows:

10 The work sheet as an envelope or bill to be printed upon is placed upon the bed 11 of the machine beneath the tracks 14 and 15 and between the sectors 25 and 26. As said sectors are rotated, the proximate ends 15 thereof are moved inwardly toward each other and into engagement with the sheet and also with the stencil superimposed thereon in said stencil track; and press the two together. Due to the rotation of said sectors, the stencil and the sheet are moved simultaneously toward the delivery end of the machine end, at the same time, the impressions borne by the stencil are impressed 20 on the sheet by ink carried by the face of the upper sector 25 which ink is forced through the impression in the stencil.

The surface of the upper sector may be maintained in inked condition by suitable means as the ink roll 73 which roll is supplied with ink from an ink reservoir 77, which is pivotally supported forwardly of the stencil receiver. A toothed ink wheel 78 is rotatably mounted within said ink reservoir, and with the periphery thereof immersed in the ink. A transfer roll 80, which preferably is of felt or other absorbent material, is disposed above said ink reservoir and is adapted to be held yieldingly against and in rolling engagement with the ink roll 73 whereby to be rotated as the printing sector 25 rotates said ink roll. Ink is applied to the transfer roll by moving said ink roll 70 upwardly, whereby to cause the ink wheel 78 to engage and roll in engagement with said transfer roll. Said transfer roll is rotatably supported by a bracket 83, which bracket is pivotally supported on the upper operating shaft 35. A spring 84 connected between said bracket 83 and the fixed bracket 38 serves to maintain said transfer roll 80 yieldingly in engagement with the ink roll 73.

As has been previously stated, the stencils are contained in alphabetical or other classified order in trays and are adapted to be placed in such order in the stencil holder. While the stencils, if the stencils bear names and addresses, may be arranged in alphabetical order, it is often desirable while feeding all stencils through the machine to print only from selected stencils. For instance, it may be desirable to circularize only a certain class of trade, as for instance, druggists and it is desirable that only the addresses of druggists should be selected

from the entire list of stencils for printing. It may be desirable also at one time to send mail matter to several classes of the entire list. Consequently, means are provided to indicate to the operative of the stencil printing machine, the particular stencils he should select for printing and to operate the machine to print from such stencils only and to pass all stencils other than those selected through the machine without printing from them. To this end, the stencils are provided with means to identify their particular class. The identifying means may comprise one or more punch holes or apertures 90 formed in the margin or frame of 80 the stencil and suitably spaced in the frame with relation to one edge thereof. The identifying means denoting confectionery, for instance, may be spaced a certain distance from the forward edge of the frame 85 while the identifying means denoting stationery, for instance, may be spaced a different distance from the front edge of the stencil, and so on. As the concern whose address is borne by a stencil may handle more 90 than one class of goods, the stencil may have a plurality of identifying means, or punch holes.

In combination with the stencil, as thus arranged, suitable indicating or selecting means are associated with the stencil printing machine. Said indicating or selecting means may include the U-shaped clips or indicators 93. Said clips are adapted to fit over one of the stencil tracks as the track 14 and be retained frictionally in adjusted position thereon. The upper arms of said clips are adapted to extend over the upper face of said track and terminate adjacent the perforated margins or frames of the stencils. Said clips are adapted to be so positioned upon the track in the "selecting" position between the sectors and the stencil holder, in which position the successive stencils momentarily remain stationary, as to align or register with the perforations in the stencils adapted to be selected for printing and to be out of register with the identifying means of stencils in undesired classes. 100

Said clips are properly positioned by trial to register with the perforations in the stencils to be selected or said track 14 may be calibrated and the stencils may be perforated in conformity with the calibrations 94 thereof whereby the clips initially 120 may be properly positioned on the track without a previous trial for registration.

The operation of the machine to print from selected stencils only and to pass other stencils through the machine without printing therefrom is or may be substantially as follows:

The operative may pull out the spring-pressed pin 44 whereby to release the operating handle 41 from operative connection 130

with the arm 40 and rotate said handle in a counter-clockwise direction. This serves to reciprocate the pusher to move stencils successively into and along the track and past the selector clips 93. Each complete rotation of the handle, when disconnected from the arm 40, serves to move the stencils one stencil length further along the track. During this operation, the operative 10 observes the position of the stencils with respect to the selector clips. When a stencil is introduced into the stencil track and, in the intermediate or selecting position of the stencil, one or more perforations there- 15 in are aligned or in register with one or more selecting clips 93, thereby indicating that the stencil is to be utilized for printing, the spring pressed button 44 is released whereby to lock the handle with the arm, 20 40. The handle is thereupon rotated in a clockwise position whereby to actuate the printing sectors as well as the stencil feeding mechanism. Said sectors rotate into engagement with the selected stencils and the work and move both simultaneously 25 along the track and record the stenciled impression upon the work. At the same time, the printing operation is being performed, a second stencil is moved by the 30 pusher from the stencil holder into the selector position in readiness to be engaged by the printing sectors upon the next revolution thereof. If one or more perforations in the stencil are found to be in register 35 with a selector clip 93, the operating handle 41 is again rotated in a clockwise direction for a second complete revolution thereby to record the impression borne by that stencil. If, however, none of the perforations in 40 the stencil are in register with a selector clip, this is an indication that the stencil is not to be utilized for printing. Consequ- 45 ently, the spring-pressed pin 44 is withdrawn from locking engagement with the arm 40 and the operating handle is rotated in a counterclockwise direction, thereby moving said undesired stencil along the track, and out of printing position, but without oper- 50 ating the printing sectors and, consequent- 55 ly, without recording the impressions borne by this stencil. These operations may be repeated indefinitely or for so long as there are stencils in the stencil receiver.

While the machine herein shown is so arranged that the operating handle is rotated in one direction to record the stenciled impression and rotated in the opposite direction to feed undesired stencils through the machine without printing therefrom, yet it is obvious the machine may function to print from selected stencils and reject undesired stencils upon rotating the operating handle in one direction only.

In connection with means for selecting 60 certain stencils and rejecting undesired

stencils, means are also provided for printing identical characters, as a date, for instance, upon the sheets at the same time the characters borne by the stencils are printed on the sheets.

The dating device may include a sector 110, which sector is formed or provided with a slot 111 adapted removably to hold type slugs 112. Said sector is fixed preferably detachably to the upper operating 70 shaft 35. A sector 113 is fixed to said lower operating shaft 27 and serves as a platen to support the work against the action of the type slugs carried by the upper sector. Said two sectors are so fixed to their respective shafts that they rotate together simultaneously with a corresponding movement of the printing sectors 25 and 26. The type carried by the sector 111 may be inked by suitable means as an ink roll 115, 75 which ink roll is disposed between the dating sector and the stencil holder and is rotatably mounted upon the bracket 83. Said ink roll is composed of felt or other porous ink absorbent material and is 80 adapted to be engaged and rotated by the type on said dating sector and as said dating sector is rotated. Said ink roll is adapted to contain a sufficient quantity of 85 ink to render unnecessary the re-inking of 90 said ink roll except at extended intervals. Inasmuch as the dating sector is driven with the printing sector, it is apparent that 95 the date or other characters, borne by said sector, will be impressed upon the work 100 only when the characters borne by selected stencils are also imprinted on the work.

The structure may be otherwise modified without departing from the spirit of the invention.

I claim:

1. A stencil printing machine having means to feed stencils successively into and out of a printing position, means carried by the machine to indicate certain stencils for printing, and manually actuated means to print from such selected stencils and to pass other stencils into and out of printing position without printing therefrom.

2. A stencil printing machine adapted to print from a plurality of stencils having identifying means, means to feed the stencils successively into and out of a printing position, means to indicate certain stencils for printing, including indicating means adapted to register with the identifying means of certain stencils, and manually actuated means to print from such selected stencils and to pass unselected stencils into and out of printing position without printing therefrom.

3. A stencil printing machine adapted to print from a plurality of stencils having identifying means, means to feed the stencils step by step into and out of a printing

- position, means to indicate certain stencils for printing therefrom including indicating means adapted to register with the identifying means of certain stencils during a period of rest of the stencils and manually actuated means to print from such selected stencils and to pass other stencils into and out of printing position without printing therefrom.
10. 4. A stencil printing machine adapted to print from a plurality of stencils having identifying means, means to feed the stencils progressively into a selecting position and thence into and out of a printing position, stencil selecting means including indicating means adapted to register with the identifying means of certain stencils when in the selecting position, and manually actuated means to print from such selected stencils and to pass other stencils into and out of printing position without printing therefrom.
15. 5. A stencil printing machine adapted to print from a plurality of stencils having identifying means, means to feed the stencils progressively into a selecting position and thence into and out of a printing position, stencil selecting means including indicating means disposed adjacent the path of movement of said stencils and adapted to register with the identifying means of certain stencils when in the selecting position, and manually actuated means to print from such selected stencils and to pass other stencils into and out of printing position without printing therefrom.
20. 6. A stencil printing machine having means to move stencils successively into and out of a printing position, means to indicate visually to an operative certain stencils for printing, and manual means operable at the will of the operative to print from the indicated stencils and to pass other stencils into and out of the printing position without printing therefrom.
25. 7. A stencil printing machine adapted to print from a plurality of stencils bearing identifying means, means to feed the stencils successively into and out of a printing position, and means to select stencils of a specific group for printing including adjustable indicating means disposed adjacent the path of movement of the stencils arranged to be positioned to register only with the identifying means of the stencils of such group, whereby to indicate the stencils for printing, stencil-printing means and means under control of an operative to actuate said stencil feeding and printing means manually so as to print from the selected stencils and to pass other stencils into and out of printing position without printing therefrom.
30. 8. A stencil printing machine adapted to print from a plurality of stencils having identifying means, a stencil track along which successive stencils are moved intermittently, means to select predetermined stencils for printing therefrom including indicating means disposed adjacent said track in position to register with the identifying means of the predetermined stencils only in a period of rest of said stencils, and manual means to print from the selected stencils and pass the unselected stencils along the track without printing therefrom.
35. 9. A stencil printing machine adapted to print from a plurality of stencils having identifying means, a stencil track along which successive stencils are moved intermittently, means to select predetermined stencils for printing therefrom including indicating means adjustably carried by said track in position to register with the identifying means of the predetermined stencils only in a period of rest of said stencils, and manual means to print from the selected stencils and pass the unselected stencils along the track without printing therefrom.
40. 10. A stencil printing machine adapted to print from a plurality of stencils having identifying means, a stencil track, stencil selecting means including an indicator disposed adjacent the track, means to move the stencils successively along said track and into a position opposite said indicator, whereby the identifying means of the stencils may register with the indicator, and thereafter move the stencils into and out of a printing position, and manual means to print from the registering stencils and pass the non-registering stencils into and out of the printing position without printing therefrom.
45. 11. A stencil printing machine adapted to print from a plurality of stencils having identifying means, a calibrated stencil track, means to move stencils successively into a position adjacent the calibrations of said track, whereby the indicating means of said stencils may register with a calibration, and thence move the stencils into and out of a printing position, and manual means to print from the registering stencils, and pass the non-registering stencils into and out of printing position without printing therefrom.
50. 12. A stencil printing machine having stencil printing means, stencil feeding means, a common operating member for both means, and mechanical connections between said operating member and both means arranged to be made and broken at the will of an operative.
55. 13. A stencil printing machine having superposed printing sectors, a stencil track disposed between said sectors, stencil feeding means including a reciprocal pusher operable to move stencils along said track to a position between said sectors, an oper-

ating handle common to said sectors and said pusher, a breakable driving connection between said handle and said sectors and pusher.

5. 14. A stencil printing machine having stencil printing means, stencil feeding means, a common operating member for both means, and means including breakable mechanical connections between said member and the aforesaid means whereby the stencil feeding means may be actuated successively independently of said printing means.

15. 15. A stencil printing machine having superposed printing sectors, a stencil track disposed between said sectors, means to feed stencils along said track into position to be engaged by said sectors, a clip movably positioned upon said track adjacent the stencil 20 path therein, means conjointly to rotate said sectors and operate said feeding means, means to disable said sectors and effect the operation of said feeding means alone, and means to hold said sectors in a stencil-release position.

25. 16. A stencil printing machine having means to feed a series of stencils successively into and out of a printing position, stencil

printing means, means to select certain stencils for printing and to pass other 30 stencils through the printing position without operating said stencil printing means, and other printing means arranged for operation only with said stencil printing means.

17. 17. A stencil printing machine having the 35 combination of superposed printing sectors, means to feed stencils successively between said sectors, other printing sectors arranged in fixed driving relation with said first printing sectors, and an operating member 40 for said sectors and feeding means, said operating member having a releasable driving connection with said sectors.

18. 18. A stencil printing machine having stencil printing means, stencil feeding 45 means, a common operating member for both means, and breakable mechanical connections independently connecting each means with said common operating member, whereby each means may be operated independently of the other and also whereby both means may be operated conjointly.

In testimony whereof, I have signed my name to this specification.

HARMON P. ELLIOTT.
